UNITED STATES PATENT OFFICE.

OSCAR A. KRATZ, OF HILLSDALE, OREGON.

TATTING-SHUTTLE

1,213,214.

Specification of Letters Patent. Patented Jan. 23, 1917.

Application filed April 29, 1916. Serial No. 94,424.

To all whom it may concern:

Be it known that I, OSCAR A. KRATZ, a citizen of the United States, residing at Hillsdale, in the county of Multnomah and State of Oregon, have invented certain new and useful Improvements in Tatting-Shuttles, of which the following is a specification, reference being had to the accompanying drawings.

10 This invention relates to certain improvements in tatting shuttles and it is an object of the invention to provide a novel and improved device of this general character wherein a spool may be readily and conveniently applied in operative position.

The invention consists in the details of construction and in the combination and arrangement of the several parts of my improved shuttle whereby certain important 20 advantages are attained and the device is rendered simpler, less expensive and otherwise more convenient and advantageous for use, all as will be hereinafter more fully set forth.

25 The novel features of the invention will hereinafter be definitely claimed.

In order that my invention may be the better understood, I will now proceed to describe the same with reference to the accompanying drawings, wherein—

30 Figure 1 is a view in top plan of a tatting shuttle constructed in accordance with an embodiment of my invention; Fig. 2 is a longitudinal vertical sectional view taken 35 through the device as disclosed in Fig. 1, a coacting spool being shown in elevation; Fig. 3 is a transverse sectional view taken through the device as disclosed in the preceding views at substantially the longitudinal 40 center thereof, a coacting spool being shown in elevation.

As disclosed in the accompanying drawings, 1—1 denote two elongated plates longitudinally bowed and substantially elliptical in form with their extremities pointed, and the central portion of each of said plates is provided with the opening 2 and with longitudinally alined tongues 3 struck therefrom at opposite sides of the opening 2 with the 50 free ends of the tongues 3 disposed inwardly, whereby the same may frictionally engage a flange 4 of the spool S, said spool being of a type generally employed in connection with sewing machine shuttles. Each 55 of the plates 1 at the longitudinal center of one of its margins is provided with a lateral

extension 5 terminating in an inwardly directed flange 6 adapted to overlie the flanges of the spool S to further assure the maintenance of the spool interposed between the 60 plates 1. In the form of invention herein set forth, the spool S is non-rotatable independently of the plates 1 and in the use of the device it will be understood that the shuttle is adapted to be reversed by the operator. I also find it of advantage to provide the opposite end portions of the plates 1 with the coacting sockets 1^a and heads 1^b to assure the plates 1 being maintained in proper relation. As herein embodied, the 70 heads 1^b comprise semi-spherical depressions as is thought to be clearly shown in the accompanying drawings.

It will be perceived that when one of the plates 1 is removed, the spool or shuttle 75 S can be readily wound by hand. It will also be understood that by removing both of the plates 1, the thread can be wound upon the spool or shuttle S in a conventional manner in connection with a sewing machine. 80

From the foregoing description, it is thought to be obvious that a shuttle constructed in accordance with my invention is of an extremely simple and comparatively inexpensive nature and is particularly well 85 adapted for use by reason of the convenience and facility with which it may be assembled, and it will also be obvious that my invention is susceptible of some change and modification without material departure 90 from the principles and spirit thereof and for this reason I do not wish to be understood as limiting myself to the precise arrangement and formation of the several parts herein shown in carrying out my invention in practice. 95

I claim:

1. As a new article of manufacture, a tatting shuttle comprising two elongated plates substantially elliptical in form adapted to 100 be arranged in superposed relation, said plates being provided with means to afford a mounting for a spool, each of said plates being provided at a side with an inwardly directed flange, the flange of one plate being 105 arranged at a side opposite to the flange of the second plate.

2. As a new article of manufacture, a tatting shuttle comprising two elongated plates substantially elliptical in form adapted to 110 be arranged in superposed relation, and inwardly disposed tongues carried by said

plates to afford a mounting for a spool, each of said plates being provided at a side with a depending flange.

3. As a new article of manufacture, a tatting shuttle comprising two elongated plates substantially elliptical in form adapted to be arranged in superposed relation, and inwardly disposed tongues carried by said plates to afford a mounting for a spool, the 10 adjacent end portions of the plates being

provided with coacting sockets and heads for holding the plates against relative lateral movement.

In testimony whereof I hereunto affix my signature in the presence of two witnesses. 15

OSCAR A. KRATZ.

Witnesses:

J. B. WATKINS,
